UNITED STATES PATENT OFFICE.

EDGAR B. JACKSON, OF DELAWARE, OHIO.

SHIELD FOR CULTIVATORS.

SPECIFICATION forming part of Letters Patent No. 308,166, dated November 18, 1884.

Application filed March 12, 1884. (No model.)

To all whom it may concern:

Be it known that I, EDGAR B. JACKSON, of Delaware, in the county of Delaware and State of Ohio, have invented certain new and useful Improvements in Shields for Cultivators; and I do hereby declare that the following is a full, clear, and exact description thereof, reference being had to the accompanying drawings, and to the letters of reference 10 marked thereon, which form part of this specification.

My invention relates to improvements in shields for cultivators; and the objects thereof are, first, to obviate the obstruction by 15 clods, sods, stones, &c., to the operation of the plow; second, to prevent the shovel from lifting out or covering up the plant while working deeply and close to the row; and, third, to attain these ends with simplicity of construction. I attain these objects by the mechanism 20 illustrated in the accompanying drawings, in which—

Figure 1 is an elevation of a double-shovel plow operatively, showing my improvements 25 in position. Fig. 2 is a vertical section through the axis of the shield when in position. Fig. 3 is an elevation of the flanged shield. Fig. 4 is a vertical section through the axis of the shield, taken at right angles to Fig. 2. Fig. 30 5 is a horizontal section through the end of the arm by which the shield is suspended from the sheth; and Fig. 6 is a side elevation of the spring-box and angle-arm.

Similar letters indicate corresponding parts 35 in all the views.

A is the clevis attached to the beam B by bolt C', and pivoted at C to follow the horizontal changes of the shaft or pole. The beam bifurcates to carry two shovels, M' N', bolted, 40 respectively, to the curved extensions M N.

B' B'' are the sheths to which the shield-wheel O is bolted. E represents an iron plate resting on the sheths, to which the angle-iron W, bolted to the box Y, is fastened by 45 bolt D.

F F' are the handles or stilts, curved at H H' and braced by a cross-bar, G. The handles are bolted to the beams and are capable of movement horizontally by means of slotted 50 bars I I', in which the bolts K K' operate.

L is a bolt by which the bar I is joined to

the beam, and a similar bolt (not shown) performs a similar function for the bar I'.

O is the shield-wheel. It is conical in form, so that one part of its surface is parallel with 55 the row, while the other is at an angle to it. Radial flanges P P', starting at different distances from the center, terminate in a common circle concentric with and beyond the circumference of the wheel. Their purpose is to keep clods, sods, stones, &c., from lodging on the wheel. No special care in laying these out is needed. The hub O' forms an angle of about twenty degrees with the surface of the wheel O, and the inner surface 65 is struck up to form a bed, U, within the hub O' for the accommodation, respectively, of a shaft-bolt, X, and a disk, S, which forms with a parallel disk, S', the means of shifting the arm R in a horizontal plane, and hence of altering 70 the inclination of the surface of the wheel to the row.

R is a tapering arm inwardly terminating in diamond-shaped disks R' R', which encircle the axis X and admit by their construction 75 of a limited oscillation of the arm with respect to the shield, thus regulating the angle of the shield to the row. Outwardly the arm is bolted meditately to an angle-iron, W, whose arm parallel to the plate E is fastened thereto 80 by the bolt D.

Between the upper end of the arm R and the iron W is held, by the same bolt T', a spring-box, Y, whose spring Y', abutting at one end against a lug, Z, on the arm R, movable in a 85 recess, Z', in the box, serves, by contractile force, to maintain the equipoise and depth of the wheel. The box Y has a segmental slotted flange, Y'', projecting from its outer surface, which serves to vary the relation of arm 90 and shield to the sheth and draft by shifting the bolts T T' in the slots.

S S' are counterpart disks on the axis X, whose transverse grooves permit the reciprocation of the arm R by means of the rounded 95 disks R' R'. A nut, S'', confines the headed axle X in position.

T T' are headed bolts securing the arm R and box Y to the angle-iron W.

U is a bed within the hub of the shield, in 100 which the washer X' and the squared end of the disk S are accommodated.

V is a bolt connecting the handle F to the beam B", and a corresponding bolt performs a similar function in the same relative location for the handle F'.

- 5 W is an angle-iron whose short arm is disposed parallel to the plate E and bolted thereto. The long arm is slotted to secure horizontal changes of the arm R by shifting the bolts T T' therein.
- 10 The purpose of the invention is to afford protection to the hill or plant in cultivating corn, cotton, tobacco, &c. The shield-wheel can be placed with the front side from the hub to the forward edge parallel with the 15 row, thus throwing the rear part at an angle from the row, thereby keeping the earth from covering the plant or obliterating the mark of the planter, if he desire to cultivate directly after planting. After the crop is sufficiently 20 advanced to admit of throwing a little earth around the stalks, the wheel should be placed with the face of the hub about parallel with the row and in advance of the shovel, as shown in Fig. 1. If the plants are of a bushy nature— 25 such as potatoes, corn, or cotton—the wheel should be placed, when these are advanced enough to permit some hilling up, about parallel with the row, throwing the forward edge outwardly at an angle that will force the leaves 30 or foliage of the plant on its smooth surface, gradually pressing them into the row as the wheel passes, allowing the shovel to run as close to the row as desired.

The dimensions of the shield-wheel and the 35 number, shape, and disposition of the flanges may be varied with the character of the crop being cultivated. The flanges are placed on the wheel to keep clods, sods, stones, &c., from lodging thereon, and so long as this end is 40 effectively attained their form, size, and arrangement are immaterial.

The advantage incident to the use of the shield herein described is that while one surface is parallel to the row the other is at an 45 angle thereto, and conversely, so that simultaneously two different and desirable effects are exerted upon the soil and plants by the same wheel and power. The wheel is maintained in the row by the force of the spring Y'.

50 Having thus fully described my invention, what I claim, and desire to secure by Letters Patent of the United States, is—

1. In cultivators, a conical shield-wheel having unequal radial flanges starting at different circles within the circumference and terminating in a common circle beyond the same.

2. In cultivators, a conical shield-wheel having unequal radial flanges starting at different circles within the circumference and terminating in a common circle beyond the same, in combination with an arm capable of altering its inclination to the surface of the wheel.

65 3. In cultivators, the conical shield-wheel and an arm capable of altering the inclination to its surface, in combination with a spring-

box whose contained spring overcomes all tendency of the wheel to leave the row.

4. In cultivators, the conical shield-wheel, 70 an arm capable of altering the inclination to its surface, and a spring-box the retractile force of whose contained spring is exerted to maintain the wheel in the row, in combination with devices for effecting respectively the 75 horizontal and vertical adjustment of the arm.

5. In cultivators, the shield-wheel O, perforated at U, in combination with arm R, having rounded terminal disks R' R', encircling the axis, disks S S', nut S'', washer X', and 80 headed spindle or axle X.

6. In cultivators, the angle-iron W, perforated for the insertion of bolt D, and slotted to permit horizontal variation of the arm R by nuts and bolts T T', in combination with said 85 arm, and a box, Y, the inner end of whose contained spring Y' abuts against the lug Z on said arm, movable in recess Z' in the box, whereby the contractile force of the spring is exerted to restore and maintain the shield- 90 wheel to a proper depth in the row.

7. In cultivators, the shield-wheel O, perforated at U, arm R, having a lug, Z, and rounded terminal disks R' R', encircling the axis, disks S S', nut S'', washer X', and headed 95 spindle or axle X, in combination with the angle-iron W, perforated for the insertion of bolt D, and slotted to permit horizontal variation of the arm R by bolts T T', and box Y, the inner end of whose contained spring 100 Y' abuts against the lug Z, which is movable in a recess, Z', in the box.

8. In cultivators, the box Y, containing a spring, Y', whose inner end abuts against a lug, Z, on the arm R, movable in a horizontal 105 path by any obstruction encountered in the recess Z' in the box, and having a slotted segmental flange, Y'', in combination with angle-iron W, plate E, bolt D, sheths B' B'', arm R, bolts T T', and axle X.

9. The combination, in a cultivator, of the shield-wheel O, perforated at U, having unequal radial flanges P P', terminating in a common circle concentric with the circumference of the wheel, washer X', disks S S', arm 115 R, having rounded terminal disks R' R', diamond-shaped in cross-section for purposes of strength, and a lug, Z, at its upper end capable of altering its vertical plane in a horizontal recess, Z', nut S'', spindle X, with box 120 Y, containing spring Y', and having a segmental slotted flange, Y'', radiating therefrom, angle-iron W, perforated for the insertion of bolt D, and slotted for the variable location of bolts 125 T T', substantially as herein shown and described.

In testimony that I claim the foregoing as my own I affix my signature in presence of two witnesses.

EDGAR B. JACKSON.
